TABLET CRUSHING AND DISPENSING DEVICE

Louis A. Boylan, Chicago, Ill., assignor to Walgreen Co., Chicago, Ill., a corporation of Illinois

Application May 6, 1940, Serial No. 333,633

9 Claims. (Cl. 83—12)

This invention relates to dispensers and more particularly to a combination crushing and dispensing device, although certain features thereof may be employed with equal advantage for other purposes.

It contemplates more especially the provision of a self-contained feeding, crushing and dispensing device *t* which serves to crush preformed substances such as effervescent tablets preparatory to discharge into a glass or other container for conversion into a carbonated drink.

Numerous types of tablet crushing and dispensing devices have heretofore been proposed, and with the increasing demand for carbonated drinks prepared from tablets, there is a requirement for a combined feeding, crushing and dispensing device of a portable character to enable the more efficient vending of drinks over the counter for consumption by the purchasing public. Preformed medicinal tablets are universally used for conversion into a carbonated drink since they are free from deterioration over a long period of time and may be conveniently packed for vending pre-measured units or doses that possess a distinct advantage over powders and pulverized substances used for the same purpose. Preformed tablets do not, however, dissolve sufficiently fast in water to render such desirable for over the counter preparation. It is desirable, therefore, to quickly crush the preformed tablet or tablets for conversion into minute particles that, in turn, are deposited in a glass and plain or carbonated water supplied therein for comparatively rapid conversion into a palatable drink.

In order to meet the demands and requirements of over-the-counter preparation and dispensing of carbonated drinks, however, it has been found desirable to combine instrumentalities in a self-contained portable unit for feeding, crushing and dispensing in a continuity of operations responsive to the single manipulation of a lever or other actuator without entailing much labor, time or effort. This has been accomplished by combining simple instrumentalities that are very effective for comminuting preformed substances such as tablets which are supplied from the original container and dispensed in pulverized form for ready conversion into a carbonated drink. It is not necessary or even desirable that the preformed tablets should be finely pulverized for conversion into a drink, since a fine pulverization speeds the effervescent action to such a degree that the liquid such as

carbonated water does not fully absorb the desirable ingredients of a preformed tablet.

The advantage of having a comparatively coarse or granular mass dispensed into a container for admixture with plain or carbonated water also enables more effective crushing instrumentalities which have been combined with automatic feeding and dispensing mechanism responsive to a single actuation. This speeds the preparation of carbonated drinks and provides for a more complete absorption of the beneficial ingredients incorporated into preformed tablets to serve a definite therapeutic purpose. Fine pulverized powders of similar character fizz so rapidly in water as to preclude the water absorption of a substantial portion of the active ingredients. Consequently, the total benefit is not derived therefrom.

One object of the present invention is to simplify the construction and improve the operation of devices of the character mentioned.

Another object is to provide an improved combination of feeding, crushing and dispensing instrumentalities for conversion of preformed tablets into an effervescent drink.

Still another object is to provide improved crushing instrumentalities in a dispenser for preformed tablets having an effervescent action in plain or carbonated water.

A further object is to provide improved feeding and crushing instrumentalities that are operatively connected to effect the conversion of preformed tablets into a comminuted substance deposited in a container responsive to a single stroke of the actuator.

A still further object is to provide improved feeding, crushing and dispensing instrumentalities in a self-contained device for the speedy counter preparation of effervescent drinks.

Other objects and advantages will appear from the following description of an illustrative embodiment of the present invention.

In the drawings:

Figure 1 is a front view in elevation of a machine embodying features of the present invention.

Figure 2 is a side view in elevation of the machine shown in Figure 1, parts thereof being broken away to clarify the showing.

Figure 3 is a fragmentary sectional view taken substantially along broken line III—III of Figure 1.

Figure 4 is a sectional view taken substantially along line IV—IV of Figure 2.

Figure 5 is a front view in elevation of a side

plate taken substantially along line V—V of Figure 1.

Figure 6 is a fragmentary sectional view of a tablet feeding detent taken substantially along line VI—VI of Figure 3.

Figure 7 is an enlarged sectional view taken substantially along line VII—VII of Figure 1.

Figure 8 is a fragmentary sectional view taken substantially along line VIII—VIII of Figure 2.

Figure 9 is a sectional view taken substantially along line IX—IX of Figure 7.

Figure 10 is a fragmentary sectional view taken substantially along line X—X of Figure 8, the detent being shown in its extreme inward operative position to maintain the stacked tablets against discharge.

Figure 11 is a perspective view of a scraper shown in assembled position in Figure 7.

Figure 12 is a perspective view of the feeding instrumentalities shown in assembled position in Figures 2, 3, 7, 8 and 10.

Figures 13 is a perspective view of the tablet holding detent actuator shown in assembled position in Figures 3, 7 and 10.

Figure 14 is a fragmentary sectional view taken substantially along line XIV—XIV of Figure 9.

The structure selected for illustration comprises a base plate 10 which, in this instance, is of substantially rectangular configuration to present an upraised portion 11 that is substantially U-shaped as at 12 to conform with the contour of a glass which is displaced therein and held in registry with dispensing instrumentalities to be herein-after described. The glass is supported by the base plate 10 and confined by the substantially U-shaped lateral recess 12 of the upraised base portion 11. With this arrangement, the attendant can hold the glass in one hand upon the base plate 10 to maintain the equilibrium of a vertical standard 13 and a housing 14 supported thereon.

The standard 13 is, in this instance, of substantially cylindrical configuration for attachment to the rearward region of the base 10—11 through the medium of a threaded fastener or stud 15 that projects axially therethrough for engagement with the standard 13 and the housing 14. To this end, the upraised portion 11 is provided with a slightly countersunk circular recess 16 which corresponds in size with the external diameter of the standard 13 that is in registry therewith for anchored engagement with the base 10—11. Any suitable ornamentation such as the rings 17—18 may be forced on the standard 13 to conform with any desired design or outline providing an attractive appearance.

The upper end of the cylindrical standard 13 cooperates with a countersunk boss 19 formed rearwardly along the longitudinal median line of the housing bottom 14. The stud or bolt 15 has a polygonal nut 20 threaded thereon to hold the housing 14 (Figure 3) to the standard 13 and the base 10 in rigid assembled relation. The housing 14 is of substantially rectangular configuration and presents a correspondingly shaped interior chamber 21 defined by the enclosed end walls 22—23—24—25 and a side wall 26 that are, in this instance, integrally formed to constitute the chambered housing 14. A side plate 27 is shaped to correspond with and serves as a complement of an open face 28 of the housing 14, it being detachably associated therewith by means of fasteners such as a plurality of threaded studs 29 which project through apertures 30 therein for threaded engagement with correspondingly shaped internally threaded bores 31 provided in the housing face 28.

The housing chamber 21 is enclosed by the side plate 27 which corresponds in shape and appearance with the side wall 26 of the housing 14 to confine feeding, crushing and dispensing instrumentalities to be herein-after described. The casing 14 serves to support an inverted container such as a tablet confining bottle 32 which, in this instance, is preferably through not essentially of cylindrical configuration conforming for appearance purposes with the standard 13. The container 32 confines a plurality of preformed tablets 33 in superposed stacked relation for protective storage therein by virtue of a cap (not shown) that serves to hermetically seal the tablets 33 against exposure while in storage on the shelves of the vendor. The closure cap can be removed and the container 13 inverted for engagement with a resilient gripping ring 34 molded or otherwise shaped from resilient material such as rubber.

The gripping ring 34 is received within and tightly engages the countersunk bore 35 of a somewhat smaller diameter than the ring 34, the bore 35 being provided in an upraised portion 36 formed integral with a depending boss 37 comprising part of the casing 14 in the upper end wall 23 thereof. It should be observed, therefore, that the tablets 33 will be confined in stacked relation in the container 32 for communication with an axial orifice 38 that extends through the boss 37 to communicate with the interior of the tablet container 32. In order to support the tablets 33 within the inverted container 32, the orifice thereof is valved by a plate 39 pivoted to confront the superposed tablets 33 in the housing orifice 38.

To this end, the valve plate 39 is provided with spaced ears 40 that have aligned bores 41 therein to receive a pintle 42 therethrough for threaded engagement with an end wall 26 of the housing 14 serving as an anchor therefor. The retaining nut 43 engages a free end of the pintle 42 to retain the valve plate 39 and to serve as a mount therefor. A spring 44 is anchored at one extremity thereof to the valve plate 39 below the pintle support therefor by engaging a pin 44' thereon while the other spring extremity is anchored as at 45 to the interior of the housing 14, thereby urging the valve plate 39 in a clockwise direction (viewed from Figures 3 and 7) for normally supporting the tablets 33 in superposed relation within and above the orifice 38 which communicates with the inverted container 32 detachably associated with the resilient gripping ring 34 serving to seal the container 32 to the interior 21 of the housing 14.

A valve trip 46 terminates in the apertured boss 37 opposite to the pintle 42 between the spaced ears 40 and the valve plate 39, the latter being slotted as at 47 to receive the trip 46 therebetween and to engage therewith in a counter-clockwise direction to impart corresponding pivotal movement to the valve plate 39 against the urge of a spring 44 to release the lowermost tablet 33 and permits its displacement responsive to the urge of gravity between confronting crushing rollers 48 and 49. The crushing rollers 48 and 49 are provided with axial stub shafts 50 and 51, respectively, which are journaled in the side walls 26—27 of the housing 14.

To this end, the side walls 26—27 are each provided with a pair of horizontally aligned inwardly projecting bosses 52 and 53 that are bored to receive the shafts 50—51 to rotatively support the crushing rollers 48—49 in horizontal spaced alignment within the chamber 21 of the housing 14. As shown, the shaft 50 projects outwardly

through the detachable housing plate 37 to receive a handle 54 that terminates in a boss 55 suitably bored to engage the driving shaft 50. A set screw 56 extends through the housing boss 55 to engage the driving shaft 50 so that the handle 54 will rotate therewith to turn the roller 48.

As shown, the rollers 48-49 are provided with spur gears 57 and 59 that mesh with each other so that the rotation of the roller 48 responsive to the handle 54 will impart opposite rotation to the rollers 48-49. The rollers 48-49 are spaced from each other at a distance that is somewhat less than the thickness of the tablets 33 which are compelled to pass therebetween. It should be noted that the spur gears 57-58 are pressed onto the shafts 50-51 to rotate in unison therewith and the crushing rollers 48-49 that are attached thereto. So that the crushing action upon the tablets 33 will be effective, the peripheries of the rollers 48-49 are provided with a series of uniformly spaced circumferential cutting edges 59 and 60, respectively.

The uniformly spaced cutting edges 59-60 effect the crushing or comminution of the pre-formed tablets 33 into particles responsive to a fractional turn of the rollers 48-49 with a tablet 33 passing therebetween. The limit of turning movement imparted to the rollers 48-49 responsive to the handle 54 is controlled by a stud 61 that is pressed into a somewhat smaller bore 62 formed in the upraised portion 63 of the detachable plate 27 (Figures 5 and 8). The stud 61 projects in an arcuate slot 64 provided in the roller 48 (Figure 7) so that the limit of rotation is determined by the extent of the arcuate slot 64 that is in registry with the stud 61 projecting therein from the housing plate 27.

In order to provide for the automatic feeding of the tablets 33 between the crushing rollers 48-49, a lug 65 is attached to the surface of the roller 48 by means of a threaded stud 66 projecting therethrough. The lug 65 is disposed in the path of the trip 46 so that the return movement of the handle 54 will displace the crushing roller 48 in a clockwise direction (viewed from Figure 7) and momentarily pivot the valve plate 39 in a counterclockwise direction to direct the gravity displacement of the tablet to a position between the rollers 48-49.

During this momentary tilting of the valve plate 39, all of the tablets above the lowermost one pivotally supported thereby are held in suspended supported position by means of a detent 66 that is reciprocally mounted diametrically through the housing boss 37 so that the free extremity thereof will engage the second lowermost tablet 33 (Figure 10) and serve as a support for the tablet superposed thereabove for confinement in the bottle or container 32 and simultaneously releasing the lowermost tablet responsive to the momentary counterclockwise displacement of the valve plate 39 against the urge of the spring 34.

In order that the detent 66 should coordinate with the movement of the valve plate 39, the detent 66 terminates in a threadedly connected head 67 (Figure 7) that has oppositely extending trunnions 68 provided thereon to register with slots 69 provided in the furcations 70 of a lever 71. The lever 71 is pivoted at its lower extremity to a pin 72 that extends through the aperture 73 provided therein (Figure 13). The pin 72 may take the form of a threaded stud that is anchored on the wall 26 of the housing 14 to serve as a support for the lever 71 that is

normally urged in a counterclockwise direction (viewed from Figure 7) by a flat spring 74 attached to the lower region thereof by means of a threaded stud 75.

As shown, the flat spring 74 has an angularly offset extremity 74' that engages the end wall 23 of the housing 14 to normally urge the detent 66 toward the left (viewed from Figures 3 and 7) to engage the second lowermost tablet 33 and serve as a support for the superposed stack of tablets 33. This permits the lowermost tablet 33 to be subject to the position and support of the valve plate 39 and it is momentarily actuated responsive to the oscillation or clockwise rotation of the roller 48 to place the tablet between the crushing rollers 48 and 49 preparatory to the next actuation of the handle 54 in a counterclockwise direction (viewed from Figure 2) to effect the crushing thereof.

It will be observed that the lug 65 will actuate the trip 46 in a clockwise direction (viewed from Figure 10) and preventing the counterclockwise displacement of the handle 54 without effecting the position of the valve plate 39 because the latter only responds to the trip 46 when displaced in a counterclockwise direction preventing the return movement of the instrumentalities such as the handle 54 and the crushing rollers 48-49.

This cycle of operations can be repeated so long as the supply of tablets in the container 32 affords the dispensing thereof to the crushing rollers 48-49 which serve to comminute each tablet 33 in response to a fractional turn thereof as effected by the handle 54 within the limits of the arcuate slot 64. It will be observed that after the valve plate 39 returns to its operative horizontal position beneath the orifice 38 to support the entire superposed stack of tablets 33 the lug 65 is within range of the arcuate recess 76 provided in the face of the detent lever 71 to retain the latter in its extreme clockwise position against the urge of the flat spring 74 so that the detent 66 will be positively free and disengaged from the second lowermost tablet 33.

While the lug 65 is in a position to actuate the valve plate 39 to permit the gravity displacement of the lowermost tablet to the rollers 48-49, the lever 71 is free for displacement in a counterclockwise direction (viewed from Figure 3) responsive to the urge of the flat spring 74 so that the detent 66 will be in effective engagement with the second lowermost tablet 33 to preclude more than a single tablet from being dispensed for each actuation of the handle 54.

The handle 54 simultaneously controls the feeding, crushing and dispensing operations without exercise of any control other than the movement of the handle 54 by the attendant who has his other hand free to hold the glass on the base plate 10 to maintain the instrumentalities in the desired position.

It will be observed that the tablets 33 can be successively fed and comminuted into particles of selected fineness depending upon the depth and spread between the circumferential cutting edges 59-60. It should be noted, however, that the circumferential cutting edges 59-60 should be of sufficient depth and spread to provide an effective cutting and comminuting action. Mere roughened or knurled surfaces would not ordinarily be considered satisfactory for effecting the total comminution of each tablet 33 responsive to a full or fractional revolution 75 of the rollers 48-49.

So that the grooves that are alternately disposed between and define the circumferential cutting edges 59-60 may be kept clean and the comminuted substances guided to a discharge opening 71 provided in the bottom end wall 25 of the casing 14, a pair of plates 78 and 79 are, in this instance, inclined to converge upwardly so that their top edges may be serrated as at 80 to serve as a complement of the circumferential cutting edges 59-60 for frictional engagement with the peripheries of the rollers 48-49.

To this end, the plates 78-79 are anchored to substantially rectangular brackets 81 and 82 which have confronting inclined surfaces 83 and 84, respectively, for attachment of the scraper blades 78-79 thereto. Screw fasteners 85 project through the bottom of the plates 78-79 to engage the brackets 81-82 to properly support the scraper blades 78-79 in their desired inclined relation below the tablets 33 and rollers 48-49 which are in peripheral frictional contact therewith. The brackets 81-82 are anchored, in turn, to the end wall 25 of the housing 14 for support therein.

To this end, screw fasteners 86 extend vertically through apertures 87 in the brackets 81-82 to threadedly engage the bottom housing wall 25 to retain the scraper blades 78-79 in the desired operative position. So that the comminuted substances that may pass beyond the scraper edges 80 of the plates 78-79, can be collected and deposited through the discharge opening 71, the brackets 81-82 are vertically grooved along the confronting inclined edges 83-84 intermediate the side walls thereof to define openings 88 that project vertically therethrough and communicate with the housing discharge orifice 71.

Consequently, none of the comminuted substances will be collected within the housing 14 nor around the base of the scraper blades 78-79. In order to preclude the comminuted substances from gathering in the housing 14 laterally of the discharge opening 71, the inner surface of the housing wall 26 is protected by an inwardly spaced plate 88 disposed between the gears 57-58 and rollers 48-49 for attachment by fasteners to brackets 81-82. Now, then, the side wall 27 of the housing 14 is raised as at 63 to contact the edges of the scraper blades 78-79 so that the comminuted tablets are passed entirely through the discharge opening 71 without any appreciable accumulation within the housing 14.

Should commercial practice so dictate, a recoil spring may be operatively connected to the handle 54 so that it is returned to its initial position upon release by the operator or attendant. With the arrangement of parts above described, a very simple, dependable and speedy tablet comminuting machine has been provided that does not entail any labor or require the attendant's manual feeding of the tablets 33 which are successively discharged from the container 32, comminuted and dispensed through the orifice 71 responsive to a single actuation of the handle 54.

Various changes may be made in the embodiment of the invention herein specifically described without departing from the invention or sacrificing any of the features or advantages thereof, and nothing herein shall be construed as limitations of the invention, its concept or structural embodiment as to the whole or any part thereof except as defined in the appended claims.

I claim:

1. A counter crushing and dispensing device for

preformed tablets comprising a chamber having inlet and discharge openings therein, confronting rollers journalled in said chamber between said inlet and discharge openings, there being circumferential cutting edges uniformly spaced on the periphery of said rollers to effect the comminution of the tablets, means including a handle to impart opposite rotation to said rollers to feed and comminute the preformed tablets therebetween, means for limiting the rotation of said rollers to less than a full revolution in both directions, tablet supporting and dispensing means in said chamber inlet, an auxiliary tablet supporting means that alternates in operation with said dispensing means to maintain tablets in superposed stacked relation with said chamber inlet, and means for operating said dispensing and auxiliary tablet supporting means responsive to the operation of said handle means.

2. A counter crushing and dispensing device for preformed tablets comprising a chamber having inlet and discharge openings therein, inter-gearied confronting rollers journalled in said chamber between said inlet and discharge openings, there being circumferential cutting edges uniformly spaced on the periphery of said rollers to effect the comminution of the tablets, means including a handle directly connected to one of said rollers to impart opposite rotation to said rollers to feed and comminute the preformed tablets therebetween, means for limiting the rotation of said rollers to less than a full revolution in both directions, means for feeding tablets to said confronting rollers responsive to their rotation from an initial position of inoperation, and means for returning said rollers and said last named feeding means to their initial position of inoperation after feeding and comminuting tablets within a full revolution of said rollers.

3. A counter crushing and dispensing device for preformed tablets comprising a chamber having inlet and discharge openings therein, inter-gearied confronting rollers journalled in said chamber between said inlet and discharge openings, there being deep-grooved circumferential cutting convolutions uniformly spaced on the periphery of said rollers to effect the comminution of the tablets, means including a handle directly connected to one of said rollers to impart opposite rotation to said rollers to feed and comminute the preformed tablets therebetween, roller scraper means having serrated edges complementary to said deep-grooved cutting convolutions to remove and guide the comminuted tablets to said discharge orifice, means for limiting the rotation of said rollers to less than a full revolution in both directions, means for feeding tablets to said confronting rollers responsive to their rotation from an initial position of inoperation, and means for returning said rollers and said last named feeding means to their initial position of inoperation after feeding and comminuting tablets within a full revolution of said rollers.

4. A counter crushing and dispensing device for preformed tablets comprising a chamber having inlet and discharge openings therein, confronting rollers journalled in said chamber between said inlet and discharge openings, a serrated surface on the periphery of said rollers to effect the comminution of the tablets, means including a handle to impart opposite rotation to said rollers to feed and comminute the preformed tablets therebetween, tablet supporting dispensing means in the path of said inlet opening for directing a tablet between said rollers, means en-

gagable with a tablet spaced above said dispensing means to support the tablets thereabove when said dispensing means are in operation, and means for operating said dispensing means and said last named supporting means responsive to the operation of said handle means to feed tablets between said rollers simultaneously with their rotation.

5. A counter crushing and dispensing device for preformed tablets comprising a chamber having inlet and discharge openings therein, confronting rollers journalled in said chamber between said inlet and discharge openings, there being circumferential cutting edges uniformly spaced on the periphery of said rollers to effect the comminution of the tablets, means including a handle to impart opposite rotation to said rollers to feed and comminute the preformed tablets therebetween, tilttable tablet dispensing means in the path of said inlet openings for directing a tablet between said rollers, means for operating said dispensing means responsive to the operation of said handle means, and means for holding stacked superposed tablets relative to said inlet opening during the operation of said tablet dispensing means.

6. A counter crushing and dispensing device for preformed tablets comprising a chamber having inlet and discharge openings therein, confronting rollers journalled in said chamber between said inlet and discharge openings, there being circumferential cutting edges uniformly spaced on the periphery of said rollers to effect the comminution of the tablets, means including a handle to impart opposite rotation to said rollers to feed and comminute the preformed tablets therebetween, tilttable dispensing means in the path of said inlet opening for directing a tablet between said rollers, means for holding stacked superposed tablets relative to said inlet opening during the operation of said tablet dispensing means, and means for operating said dispensing means responsive to the operation of said handle means, said last named means including trip means on one of said rollers in the path of said tablet dispensing means to operate said tablet dispensing and holding means.

7. A counter crushing and dispensing device for preformed tablets comprising a chamber having inlet and discharge openings therein, confronting rollers journalled in said chamber between said inlet and discharge openings, there being circumferential cutting edges uniformly spaced on the periphery of said rollers to effect the comminution of the tablets, means includ-

ing a handle to impart opposite rotation to said rollers to feed and comminute the preformed tablets therebetween, tilttable table dispensing means in the path of said inlet opening for directing a tablet between said rollers, means for holding stacked superposed tablets relative to said inlet opening during the operation of said tablet dispensing means, and means for operating said dispensing means responsive to the operation of said handle means, said last named means including trip means on one of said rollers in the path of said tablet dispensing means to operate said tablet dispensing and holding means in one direction, spring means for returning said tablet dispensing and holding means to their initial positions.

8. A counter crushing and dispensing device for preformed tablets comprising a chamber having inlet and discharge openings therein, confronting rollers journalled in said chamber between said inlet and discharge openings, there being circumferential cutting edges uniformly spaced on the periphery of said rollers to effect the comminution of the tablets, means including a handle to impart opposite rotation to said rollers to feed and comminute the preformed tablets therebetween, means for limiting the rotation of said rollers to less than a full revolution of both directions, tablet dispensing means in the path of said inlet opening for directing a tablet between said rollers, and means for operating said dispensing means responsive to the operation of said handle means to feed tablets between said rollers simultaneously with their rotation.

9. A counter crushing and dispensing device for preformed tablets comprising a chamber having inlet and discharge openings therein, inter-gearred confronting rollers journalled in said chamber between said inlet and discharge openings, there being circumferential cutting edges uniformly spaced on the periphery of said rollers to effect the comminution of the tablets, means including a handle directly connected to one of said rollers to impart opposite rotation to said rollers to feed and comminute the preformed tablets therebetween, tablet dispensing means in the path of said inlet opening for directing a tablet between said rollers, and means for operating said dispensing means responsive to the operation of said handle means, said last named means including trip means on one of said rollers in the path of said tablet dispensing means to operate said tablet dispensing and holding means.
